[57] CLAIM

The ornamental design in a coal analyzer or the like, substantially as shown and described.

DESCRIPTION

FIG. 1 is a front elevational view of a coal analyzer showing our new design;

FIG. 2 is a side elevational view of the analyzer of FIG. 1 looking from the left side thereof;

FIG. 3 is a side elevational view of the analyzer of FIG. 1 looking from the right side thereof;

FIG. 4 is a rear elevational view of the analyzer of FIG. 1;

FIG. 5 is a top plan view of the analyzer of FIG. 1; and FIG. 6 is a bottom plan view of the analyzer of FIG. 1;

FIG. 7 is an enlarged fragmentary portion of each ventilator shown in FIG. 4 for clarity of illustration.

The pattern shown in the rectilinear cross-hatched areas of the ventilators of FIG. 4 is uniform throughout each area.
